Charles L. Wright.

UNITED STATES PATENT OFFICE.

MORRIS PARNES, OF NEW YORK, N. Y.

LIQUID-SUPPLYING APPARATUS.

1,395,516.

Specification of Letters Patent.

Patented Nov. 1, 1921.

Application filed December 30, 1919. Serial No. 348,454.

To all whom it may concern:

Be it known that I, MORRIS PARNES, a citizen of Austria, and a resident of New York city, in the county of New York and State of New York, have invented certain new and useful Improvements in Liquid-Supplying Apparatus, of which the following is a specification.

This invention has as one of its objects 10 to provide a liquid fuel feed for internal combustion engines, in which an auxiliary tank is automatically supplied with fuel from the main tank by a partial vacuum, which latter tank may be remote, or on a 15 lower plane.

Another object is to create such vacuum in the auxiliary tank by communicating means between the tank and intake manifold of the engine.

20 A further object is to provide means for automatically controlling the vacuum relative to the level of the fuel in the dispensing tank.

25 A still further object is to provide an operative device for this purpose comprised of few and simple parts not easily liable to become deranged.

These objects are attained by the novel construction, combination and arrangement 30 of parts hereinafter described, and shown in the accompanying drawings, forming a material part of this specification, and in which:—

Figure 1 is a vertical sectional view of a 35 feed apparatus made in accordance with the invention, parts being broken away to show the construction.

Fig. 2 is an enlarged longitudinal sectional view taken through the center of the 40 valve operating means.

Referring to the drawings in detail, the numeral 10 designates a supply tank which may be remotely located and below the feed tank 11 with which it is connected by the 45 pipe 12 entering the head 14 at a point near one side.

A circular plate 15 forms the bottom of the tank 11 and also the top of the dispensing tank 16, the same having a tight lower 50 head 17, these tanks having flanged adjacent ends clamped by bolts 18 with the plate 15 intermediate.

A pipe 20 leads to the manifold of the engine (not shown) from the center of the 55 upper head 14 and fixed in the lower end of

the pipe is a spider 21 acting as a guide for a spindle 22 having attached at its upper end a perforated plunger 23 freely slideable in the pipe and normally pressed upward, away from the fixed spider, by a compression spring 24 coiled about the spindle 22. 60

The extreme end of the pipe 20 is fitted to act as a seat for the conical valve 25, in the apex of which the spindle 22 is secured, while in the base of the valve is fixed a tube 65 26 its bore 27 communicating with the tank chamber through an opening 28 formed transversely in the base of the valve 25.

The lower reduced portion 29 of the tube passes through a hollow plug or bushing 30 screw threaded into the plate 15, over which 70 is a gasket 31 contained in an inverted cap 32 through which the tube element 29 passes.

A pin 33 passes transversely through the 75 tube element 29, below the bushing 30 and pressing against the extending ends of the pin is another inverted cup 34 acting as a seat for the upper end of a coiled compression spring 35 exerting pressure upon a disk 80 valve 36 freely fitting the end of the tube and held in place thereon by the nut 37, the tube being open at its lower end, and by the passage 28, permits the passage of air between the feed and dispensing tanks in an 85 obvious manner.

Fixed in the plate 15 at one side of the center is a hollow fitting 38, its arm 39 being upturned at the center of the tank 16 and formed into a valve seat 40 to receive 90 the valve 36.

Surrounding the tube 26 is another tube 42, the same forming the central wall of an annular chamber 43 the walls 44 of which are hermetically closed, forming a float, 95 which when in a raised position contacts with the base of the valve 25, and when in a lowered position rests upon a collar 45 fixed on the tube 26, thereby closing the valve 36. 100

In order to prime the dispensing tank 16, an elbow fitting 48 is secured to one side, the same receiving a pipe 49 having a horizontally bent portion 50 its open end having rotatably mounted upon it funnel 51, normally inverted, as shown in full lines, but capable of being reversed, as indicated in broken lines, and clamped by the bolt 52, in position to receive liquid, which obviously 105 is conducted to the tank 16. 110

Set in the lower head 17 is a two-way valve 55 having a part 56 extending into the tank to prevent sediment from entering the passage 57 and which might otherwise pass 5 out of the passage 58 and be conducted by the tube 59 to the carburete (not shown) when the valve plug 60 is positioned by the handle 61 to permit passage therethrough.

Other openings 62 and 63 allow the sediment to be removed through the valve by action of the handle in an obvious manner.

In operation, the main supply tank 10 having been connected with the receiving tank 11 and the pipe 20 with the manifold 15 of the internal combustion engine with which the device is used, when the engine is in operation a suction is created producing a partial vacuum in the tank 11, causing a flow of liquid fuel therein and if continued, eventually raises the float 43 and by it closes the valve 25 cutting off the vacuum and ceasing the suction effect on the pipe 12.

A hollow fitting 38 communicating between the tank 11 and 16 maintains the latter partially filled, the valve 36 being closed only when the float is in a lowermost position, at which time the effects of the vacuum are taking place, recharging the tank 11.

Due to the springs 24 and 35 an easy and smooth action of the valves are secured, no noise or pounding taking place and it will be clear that if the connections are maintained, the filling of the dispensing tank is automatically accomplished at recurrent periods as may be required.

It will also be seen that provision has been made for manually charging or priming the tank 16 when required.

Having thus described my invention and set forth the manner of its construction, application and use, what I claim as new and desire to secure by Letters Patent, is:—

1. In an apparatus of the class described, the combination with a fuel supply source and a vacuum producing means, of a tank having an upper and lower chamber, a tubular connection between said supply source and said upper chamber, a U-shaped tubular connection between said chambers, a connection between said vacuum producing means and said upper chamber, valves controlling the passages in said last named connections, a hollow rod engaging between said valves, said hollow rod being open to both chambers above the liquid therein, and a float operable in said upper chamber whereby said valve rod is raised or lowered according to the fluctuation of said float.

2. In an apparatus of the class described, the combination with a fuel supply source and a vacuum producing means, of a tank, upper and lower chambers in said tank, a connection between said vacuum producing means and said upper chamber, a valve controlling the last named connection, a con-

nection between said chambers, a valve controlling said connection, a rod on which said valves are mounted, a spring cushion for the last named valve, and means in said upper chamber operative on the rise and fall 70 of liquid therein for actuating both of said valves simultaneously.

3. In an apparatus of the class described, the combination with a fuel supply source and a vacuum producing means, of a tank, 75 upper and lower chambers therein, a connection between said upper chamber and said supply source, a connection between said upper chamber and said vacuum producing means, a plunger movable in said last named connection, a valve carried by said plunger, a hollow stem engaged with said valve said stem extending into the lower chamber and forming an air passage between the upper and lower chambers, a hollow connection between said chambers, a valve on said stem controlling the passage in said hollow connection and a float in said upper chamber circumjacent and slidable on said stem whereby said 90 valves are automatically operated according to the quantity of liquid in said chamber.

4. In an apparatus of the class described, the combination with a fuel supply source and a vacuum producing means, of a tank 95 having a receiving chamber and a dispensing chamber, said receiving chamber being in communication with said supply source and said vacuum producing means, a hollow connection between said chambers, means for 100 priming said dispensing tank, valves controlling the passage from said vacuum producing means and said hollow connection, a tubular stem on which said valves are mounted and through which air from one 105 chamber to the other may pass, and an annular float surrounding said stem by which said valves are actuated.

5. In an apparatus of the class described, the combination with a fuel supply source 110 and a vacuum producing means, of a tank having a receiving chamber and a dispensing chamber, said receiving chamber being in communication with said supply source and said vacuum producing means, a communicating means between said chambers, said means extending slightly into said receiving chamber above the floor thereof, its opposite end being upturned and level within said dispensing chamber; means for draining said 115 dispensing chamber, reversible means for manually priming said dispensing chamber, said priming means acting as a vent when in a reversed position, means for positively clamping said priming means in either position; means communicating between said receiving chamber and the supply source, other means communicating between said receiving chamber and said vacuum producing means, valves controlling said communicat- 120 125 130

- ing means, and means in said receiving chamber for automatically actuating said valves as a unit.
6. In an apparatus of the class described, 5 the combination with a fuel supply source and a vacuum producing means, of a vacuum chamber communicating with said supply source, means for simultaneously checking the action of the vacuum producing means 10 and for draining said chamber, a dispensing chamber receptive of the fluid contents of said vacuum chamber, a U shaped tube connecting therebetween normally filled with liquid and acting as a seal; means for priming and venting said dispensing chamber, said means being always open, and means for withdrawing the contents therefrom, said withdrawing means having two distinct passages controlled by a single valve.
7. In an apparatus of the class described, 20 the combination with a fuel supply source, a tank having an upper and lower chamber, and means for forcing liquid from said supply source into the upper chamber, of a tube 25 communicating with said lower chamber, a reversible funnel-like head on the open end of said tube, and means for clamping said head to said tube in either of its adjusted positions.
8. In an apparatus of the class described, 30 the combination with a compartmented tank having upper and lower chambers, means for supplying the upper chamber with fuel, a vacuum system communicating with said upper chamber, a tubular connection between said chambers, a float operable in said upper chamber, a tubular guide operable by said float, and valves at the ends of said guide adapted to close said vacuum system or said chamber connection according to the 35 position of said float, said guide acting as an air vent for said chamber.
9. In a tank for a vacuum feed system, a 40 float carrier having a tubular stem, means at one end of said carrier stem adapted to control the vacuum connection, and means at the other end of said stem to close the discharge from said tank, said stem acting as an air vent for said tank.
- In testimony whereof I have signed my 45 name to this specification.
- MORRIS PARNEs.
